UNITED STATES PATENT OFFICE.

KIRTLAND C. BARTON, OF NATIONAL CITY, ILLINOIS.

MAT OR CLOTH FOR OIL CAKES.

Application filed July 18, 1921. Serial No. 485,704.

To all whom it may concern:

Be it known that I, KIRTLAND C. BARTON, a citizen of the United States, residing at National City, Illinois, have invented new and useful Improvements in Mats or Cloths for Oil Cakes, of which the following is a specification.

This invention relates to mats or cloths for oil cakes.

10 An object of the invention is to provide a mat or cloth for an oil cake with means responsive to the energy of an electro magnet for engagement with the electro magnet, whereby as the electro magnet is moved or 15 rotated the mat or cloth will be stripped from the oil cake.

Another object of the invention is to provide a mat or cloth for oil cakes with a metallic member adapted to engage with the 20 rotary element of a stripping machine, whereby the mat or cloth will be held and wound around the rotary element without damage to the mat or cloth.

Various other objects and advantages of 25 the invention will appear from the following description, reference being made to the accompanying drawing, in which

Fig. 1 is an elevation of a part of the machine, having my improved mat or cloth 30 thereon and engaged with the rotary electro magnet of the machine.

Fig. 2 is an end elevation.

Fig. 3 is a view showing the metallic plate in connection with the mat or cloth which 35 is drawn into engagement with the magnet as the machine is operated.

The machine, with which my invention is arranged to cooperate for the purpose of stripping the mat or cloth from the oil cake, 40 comprises a table 1 for supporting the mat or cloth and the cake enclosed thereby, as well as the operative mechanism by which the cloth is stripped from the cake. The shaft 2 is supported horizontally above the 45 table for rotation in opposite directions. It is known that the shaft 2 is rotated in one direction to strip the mat or cloth from the oil cake. The rotation of the shaft in stripping the mat or cloth from the oil cake winds the mat or cloth about the shaft. After the mat or cloth has been 50 stripped from the oil cake and wound about the shaft, the direction of rotation of the shaft is changed so as to unwind the mat or cloth therefrom. The mechanism for rotating the shaft in alternately

opposite directions comprises no part of the present invention, and therefore, is not shown or described.

The machine comprises an electro magnet 60 3 removably secured upon the shaft 2 above the table 1, and including a number of washers 4 having shoulders 5 thereon. It is to be understood that the magnet is energized as an incident to rotation of the shaft 65 2 in the direction to wind the mat or cloth on the magnet; and the magnet is de-energized automatically and as an incident to reverse rotation of the shaft.

70 My invention comprises a device in connection with the mat or cloth 6 which will be drawn into the engagement with the electro magnet automatically when the cake and cloth are placed upon the table. The machine is operated with the electro magnet 75 energized. As shown, the device mentioned is in the form of a resilient metallic strip 7, supported from one end of the mat or cloth by flexible connections 8. The connections 8 may be and preferably are short 80 metal plates having their outer ends secured to the plate or strip 7 and their opposite ends secured to the end of the mat or cloth 6. As shown the connections 8 are of sufficient length to pass through slots 7^A near the 85 ends of the plate or strip 7 to support said plate spaced slightly from the end of the mat or cloth. The connections 8 are doubled to receive the end of the mat or cloth between the arms thereof and are secured to 90 the mat or cloth by rivets 9.

In operation, the oil cake with the cloth thereon is placed upon the table 1 in about the position shown. The shaft 2 is rotated in a counter clock-wise direction (Fig. 1), the electro magnet 3 being energized when the shaft is so rotated. The plate or strip 7 is attracted to and held in connection with the electro magnet by the energy of the magnet; but should the plates or strips 7 slip upon the magnet, it will be caught by the shoulders 5 and thereby positively prevented from slipping further. As the electro magnet continues to rotate the mat or cloth is wound on the magnet and stripped from the cake, as is well understood. When the mat or cloth has been stripped from the cake, the shaft and magnet are rotated in the direction opposite from that in which they were rotated during the winding of the 105 mat or cloth thereon.

110 My present invention may be readily used

in a machine without the usual hook-shaped, cloth-gripping elements for engaging the cloth. The hooks heretofore generally used sometimes catch into the clothing of the 5 operator of the machine, or into the flesh of the arms and hands of the operator, resulting in serious injuries. My present invention eliminates nearly all danger to the operator, and overcomes various other difficulties.

From the foregoing it will be seen that my invention satisfactorily accomplishes all of its intended purposes. The specific form and arrangement may be varied without departing from the principle of the invention. 15 I do not restrict myself to unessential features, but what I claim and desire to secure by Letters Patent is:—

1. The combination with an oil cake mat 20 or cloth, of a metallic strip attached to and spaced from one end of the mat or cloth for the purpose described.

2. The combination with an oil cake mat or cloth, of a metallic strip, and connections uniting the metallic strip with one 25 end of the mat or cloth and at a slight distance therefrom.

3. The combination with an oil cake mat or cloth, of a metallic strip, and connections uniting said strip permanently with one 30 end and near the side edges of the mat or cloth and at a slight distance from the end of the cloth.

4. The combination with an oil cake mat or cloth, of a flexible metallic strip, and 35 flexible connections uniting said strip with one end of the mat or cloth.

5. The combination with an oil cake mat or cloth, of a flexible metallic strip, and flexible connections uniting said strip with 40 one end of the mat or cloth and holding the strip spaced from the end of the mat or cloth.

KIRTLAND C. BARTON.
